EDMUND J. FEENY, OF MUNCIE, INDIANA, ASSIGNOR TO THE FEENY MANUFACTURING COMPANY, OF MUNCIE, INDIANA, A CORPORATION OF INDIANA.

RAVELING PICK-UP.

1,195,455.

Specification of Letters Patent. Patented Aug. 22, 1916.

Application filed June 8, 1914. Serial No. 843,637.

To all whom it may concern:

Be it known that I, EDMUND J. FEENY, a citizen of the United States, residing at Muncie, in the county of Delaware and State of Indiana, have invented a new and useful Raveling Pick-Up, of which the following is a specification.

In the operation of vacuum cleaners much difficulty has been experienced by the failure 10 to pick up ravelings, especially when these have become wholly or partly embedded in the nap of the carpet.

It is the object of my present invention to overcome this difficulty. In accomplishing 15 this object I provide a brush and preferably associate it with the nozzle of the vacuum cleaner, which brush is mounted so that it rolls freely on the surface to be cleaned when the nozzle is moved over such 20 surface in one direction (preferably the receding stroke), but rolls less freely or not at all when the nozzle is moved in the other direction (preferably the advancing stroke), thus rubbing on such surface. During each 25 stroke in the latter direction, the brush by its rubbing acts effectively to entangle on itself, in whole or in part, all threads and ravelings on the surface passed over, while on the alternate strokes, or those in the first 30 direction, the rolling of the brush causes the threads and ravelings thus entangled to be wound up on the brush. The rotation of the brush is preferably a mere rolling on the floor surface, instead of a reverse rotation such as ordinary carpet sweepers have. 35 The brush is conveniently mounted so that it can be thrown into and out of action at pleasure.

The accompanying drawings illustrate my 40 invention.

In these drawings Figure 1 is a front elevation, with some parts broken away, of a vacuum cleaner nozzle equipped with one form of my raveling pick-up; Fig. 2 is a 45 section on the line 2-2 of Fig. 1 but with the brush and its shaft in elevation; Fig. 3 is a plan view of one end of this form of raveling pick-up and its mounting; Fig. 4 is a section on the line 4-4 of Fig. 3, and 50 also shows the shaft in section at its flattened end portion; and Fig. 5 is a perspective view showing a complete hand operated vacuum cleaner equipped with my raveling pick-up.

55 I have illustrated my invention in connec-

tion with a vacuum cleaner in which the nozzle 10 is connected at the lower end of a dust cone 11, from the upper end of which a pipe 12 projects, this pipe 12 carrying between its ends a piston 13 around which fits 60 a cylinder 14 provided with a handle 15 whereby it may be reciprocated manually along the pipe 12, proper valves (not shown) being provided for causing this reciprocation to produce suction within the 65 nozzle 10. However, this particular form of vacuum cleaner is shown merely by way of illustration.

Projecting from the forward side of the nozzle 10 are two lugs 20 which on their 70 adjacent sides are provided with notches 21 for receiving the bent ends of spring arms 22 on a brush casing 23, there being two notches 21 in each of the arms 20 for holding the brush casing either down against 75 the floor, as shown in full lines in Figs. 2 and 4, or raised from the floor as shown in dotted lines in Figs. 2 and 4. The sides of these notches 21 are preferably beveled, so that in coöperation with the bent ends of 80 the spring arms 22 they will act as yielding latches for holding the brush casing in either position while still permitting such brush casing to be moved from such position by the application of sufficient force 85 thereto, the beveled sides of the notches acting to spring together the ends of the arms 22 when the brush casing is being moved from one position to the other. The bent ends of the spring arms 22 are provided with fingers 24 which project through 90 holes 24' in the lugs 20, to furnish a pivotal support for the arms 22. These parts I have shown in connection with all the three 95 forms of raveling pick-ups which I have illustrated, although they are not in all cases essential.

In the form of raveling pick-up shown in Figs. 1, 2, 3, and 4, each end of the brush casing 23 is provided with a notch 25, which 100 is open downward and is shallower at its forward end than at its rearward end to provide a shoulder 26. The whole brush casing 23 is open at the bottom, and mounted within it is a cylindrical brush 27 the shaft 105 of which has flattened end portions 28 projecting into the notches 25. These flattened portions 28 in their greatest transverse dimension exceed the width of the deeper part 110 of the notch 25 but not that of the shallower

part thereof. Thus when there is tendency to rotate the brush 27 in a clockwise direction (as seen in Figs. 2 and 4), the flattened end portions 28 of the brush shaft strike the shoulder 26 and roll out of the deeper portions of the notch 25, so that such rotation is merely permitted; while when there is a tendency to rotate such brush in the opposite or counter-clockwise direction the flattened end portions 28 of the brush shaft roll into the deeper portions of the notches 25 and lock between the shoulder 26 and the rear side of the notch 25 to prevent the brush from rotating, as shown in dotted lines in Fig. 4.

With the parts as shown in full lines in Figs. 2 and 4, the brush 27 engages the floor surface, and as the nozzle 10 is pushed forward over such floor surface there is a tendency to rotate the brush 27 in a counter-clockwise direction, by reason of the friction of such brush with the floor surface; but because of the locking of the end portions 28 of the brush shaft in the deeper portions 25 of the notch 25, the brush is prevented from rotating and rubs on the floor surface, so that it entangles on itself, in whole or in part, any ravelings, threads, or lint which may be on the surface passed over. However, when the nozzle 10 is moved backward over the floor surface, the tendency for the brush to rotate is reversed, and such brush turns freely in a clockwise direction to wind up on itself the ravelings, lint, and threads which it has entangled, such rolling being permitted because the flattened ends 28 of the brush shaft ride out of the deeper but narrower portions of the slots 25 into the wider portions of such slot to free such ends from the locking action of the shoulder 26.

In order to hold the brush 27 in place in the brush frame 23 when such frame is not in contact with the floor surface, I provide a spring latch which normally substantially closes the free end of each notch 25, but is preferably opposite a round portion of the shaft instead of a flattened portion thereof, so that it is not necessary to close such free end of the notch as completely. As shown, this spring latch takes the form of a spring wire 30 bent as shown in Fig. 4, such spring wire having its ends 31 extending through holes in the brush frame 23, intermediate projecting portions 32 which extend toward each other across the notch 25 near its open end, the two projecting portions 32 being joined above the notch 25 by a yoke portion 33. The two projecting portions 32 readily separate to permit the ends 28 of the shaft of the brush 27 to pass when the brush is either removed from or put in place in the brush frame.

I claim as my invention:

In combination, a rotatable brush having a projecting flattened shaft end, and a frame provided with a notch for receiving such shaft end, said notch having a portion which is wide enough to receive said shaft end and narrow enough to prevent turning of such shaft end therein and another portion which is wide enough both to receive such end and to allow it to turn therein.

In witness whereof I have hereunto set my hand at Muncie, Indiana, this 28th day of May, A. D. one thousand nine hundred and fourteen.

EDMUND J. FEENY.
